UNITED STATES PATENT OFFICE.

EUGENE S. HAYFORD, OF NEW ORLEANS, LOUISIANA.

APPARATUS FOR RAISING SUNKEN SHIPS.

1,228,914.

Specification of Letters Patent. Patented June 5, 1917.

Application filed July 31, 1916. Serial No. 112,335.

To all whom it may concern:

Be it known that I, EUGENE S. HAYFORD, a citizen of the United States, residing at New Orleans, in the parish of Orleans and 5 State of Louisiana, have invented certain new and useful Improvements in Apparatus for Raising Sunken Ships, of which the following is a specification, reference being had therein to the accompanying drawing.

- 10 This invention relates to improvements in apparatus for raising sunken ships, one object of the invention being the provision of a flexible envelop capable of being collapsed and inflated, which is so constructed when 15 collapsed as to be readily pulled into place within the ship, so that the same may be readily inflated to displace the water within the ship so that the ship may be readily floated.
- 20 A further object of this invention is the provision of an auxiliary inflatable envelop within the main envelop which provides a means to float the main envelop in position for this final inflation, after the main envelop has been pulled in to position within 25 the ship.

A still further object of this invention is the provision of a collapsible envelop provided with a compensating valve, whereby 30 as the ship is being raised, due to the buoyancy of the envelops, and the water pressure is consequently decreased, the air pressure within the envelops will be automatically decreased to prevent the bursting of the 35 envelops.

In the accompanying drawings:—

Figure 1 is a longitudinal sectional view through the ship, showing one of the envelops in place and inflated, and the second 40 envelop being pulled in to place.

Fig. 2 is an enlarged detail side elevation of one of the envelops inflated.

Fig. 3 is a longitudinal sectional view thereof.

45 Fig. 4 is a cross section taken on line 4—4 of Fig. 2.

Figs. 5, 6 and 7 are detail views of the compensating valve.

Referring to the drawings, the numeral 50 10 designates the main envelop, any number of which may be used in raising a sunken ship 11, one end of the envelop 10 being provided with a loop or ring 12, by means of which a cable 13 may be attached thereto, 55 or by means of which a diver may properly

pull the envelop in place to assume the position as shown in Fig. 1.

The opposite end of the envelop 10 is provided with an air tube 14 which leads above the surface of the water and is adapted to 60 have connected thereto an air supplying means whereby the envelop 10 may be inflated.

In order to provide a means for automatically releasing the air from the envelop 10, 65 due to the reduction of water pressure as the envelop moves upward, due to the buoyancy thereof, an annular opening 15 is provided in the bottom of said envelop, and a disk or diaphragm 16 of larger diameter 70 than the opening 15 is secured upon the exterior of the envelop by the annular flange member 17 which normally holds the disk 16 to close the opening 15, there being a plurality of openings 18 formed through 75 the diaphragm 16 and normally closed by the body of the envelop adjacent the circumferential edge of the opening 15. Thus, it will be seen that under normal conditions, the water pressure will hold the disk 16 80 seated until such pressure is overcome by the air pressure within the envelop 10.

The disk or diaphragm 16 may be constructed of a flexible material such as corrugated copper, bronze, or rubber, the same 85 being so proportioned in shape that it will expand or bulge outwardly at any desired pressure from within the envelop so as to cause the annular openings 18 to be placed in communication with the opening 15, the 90 flange or annular member 17 permitting this, but preventing the disk or diaphragm from being entirely disconnected.

In order that the envelop may be properly moved into position against the under 95 side of the ship, there is mounted within each envelop an auxiliary tube or envelop 19, the same being adhesively or otherwise secured to the incasing envelop 10, and itself being provided with a small air tube 20 100 adapted to receive air from the pump or other air supplying means, as such tube 20 is extended through and within the tube 14.

It will thus be seen that with the auxiliary tube 19 deflated, and the tube 10 also deflated, the present envelop may be positioned as shown in Fig. 1, and that by the inflation of the auxiliary tube or envelop 19, the envelop 10 will be floated and held against the under side of the ship's deck, so that 110

the same will assume the proper position to be fully inflated when air is forced into the envelop 10.

From the foregoing description, it is evident that a collapsible and flexible envelop or air tube that can be readily pulled down into the hold of the sunken vessel is provided, and that the same may be inflated to a pressure slightly above that of the surrounding water so as to displace the water simultaneously with the inflation of the tube, and thus providing a means when any number of these envelops are employed to render the ship or vessel buoyant, so that it will float to the water's surface.

By providing the compensating valve, the reduction of the water pressure as the vessel nears the surface will be taken care of, the air being permitted to escape from the envelops at the proper rate, so as not to materially reduce the buoyancy thereof, yet at the same time preventing the bursting of the envelop.

What I claim as new is:—

25 1. An apparatus for raising sunken ships, including a collapsible and inflatable envelop, means for supplying air thereto, and an auxiliary inflatable envelop mounted therein and constituting a buoyant support for the main envelop.

30 2. An apparatus for raising sunken ships,

including a collapsible and inflatable envelop, means for supplying air thereto, an auxiliary inflatable envelop mounted therein and constituting a buoyant support for the main envelop, and means connected to one end of the main envelop for directing the same in to position.

3. An apparatus for raising sunken ships, including a collapsible and inflatable envelop, means for supplying air thereto, an auxiliary inflatable envelop mounted therein and constituting a buoyant support for the main envelop, and a compensating valve carried by the main envelop for permitting the escape of air due to the reduced pressure of the water.

4. An apparatus for raising sunken ships, including a collapsible and inflatable envelop, means for supplying air thereto, an auxiliary inflatable envelop mounted therein and constituting a buoyant support for the main envelop, and a compensating valve carried by the main envelop for permitting the escape of air due to the reduced pressure of the water, said valve including a diaphragm provided with a plurality of openings adjacent the circumference thereof, and means for holding the same for limited movement over its valve port.

In testimony whereof I affix my signature.

EUGENE S. HAYFORD.
